UNITED STATES PATENT OFFICE

THEOPHILUS KALLMEYER, OF WILLOWBROOK, CALIFORNIA

BOILER FEED REGULATOR

Application filed September 26, 1928. Serial No. 303,451.

My invention is a boiler feed regulator regulating and supplying the feed water to a steam boiler.

An object of my invention is the construction of a regulator for the feed water for a steam boiler in which the regulator mechanism is not subjected to the direct action of steam from the boiler, and operates with the feed water on one side from a pump and the water passing to the boiler on the other side of the regulator.

Another object of my invention is the positive action of the regulator by means of a float, the float operating in accordance with the water level of the boiler and being subjected to the boiler steam pressure, this float operating a rocking lever having the fulcrum shaft journaled in a water and steam tight construction.

Another object of my invention is the construction of a regulator valve in a plurality of shiftable elements so that one of the elements may first be displaced to give a partial release of the pressure and subsequent to this the main valve element is raised from its seat to allow the flow of water from the pressure pump to the boiler.

In constructing my invention I utilize a suitable chamber in which a float is mounted, this chamber being connected at the bottom with a fitting having a pipe connected to the lower part of the boiler for water. The upper part of the chamber is connected to the upper part of the boiler for the flow of steam and the float is mounted in this chamber.

The float has a rod depending downwardly therefrom which engages one arm of a lever. The fulcrum shaft to which this arm is connected passes through a water tight journal in the fitting and on the other end of this shaft there is the continuation or second arm of the fulcrum lever. This second arm has a valve rod connected thereto and extending upwardly, this rod having a stem at the top with a shoulder positioned slightly below the top. The stem is adapted to extend above the valve seat. On the outside of the seat there is a tubular structure closed at the top with a plurality of slots therein for free passage of water, and surrounding this tubu-

lar structure there is a pipe with a connection to the pressure pump supplying the feed water. The fitting on the valve side of the journal has a connection to the boiler to carry the feed water.

The valve is constructed with a main element bearing on the valve seat, this element having a tubular passage therethrough in which the stem of the valve rod fits. Above the main element there is a secondary tubular valve element forming a closure against the main valve element and slidable in a second tubular structure closed at the top. The second element has a valve plug seated on the top with a pin extending downwardly below said element adapted to be engaged by the valve stem. Therefore, when the float is lowered by the lowering of the water in the boiler the valve rod is thrust upwardly, the stem first engaging the pin and lifting the valve plug, allowing a partial equalization of the pressure between the pump side and the boiler side of the valve. On increased movement upwardly the secondary valve element is raised by the stem and a small flow of water may take place from the pressure pump to the boiler. On a still further lifting of the valve rod the collar on the stem elevates the main valve element above its valve seat allowing free flow of water from the pump to the boiler.

Another main object of my invention is the construction of the valve in a plurality of series of elements, in which the unseating of a third element will effect the unseating of the second element by hydraulic action, and the unseating of the second element by such action causes the unseating of the main valve element by hydraulic action.

My invention is illustrated in the accompanying drawings, in which:

Fig. 1 is a side elevation of my invention showing its attachment to the boiler,

Fig. 2 is a longitudinal vertical section through the pressure chamber showing the float mounted therein,

Fig. 3 is an enlarged vertical cross section on the line 3-3 of Figs. 1, 4 or 5 in the direction of the arrows through the fulcrum shaft of the fulcrum lever,

Fig. 4 is a vertical longitudinal section on the line 4—4 of Fig. 3 in the direction of the arrows showing the regulating valve closed,

Fig. 5 is a section similar to Fig. 4 with the regulating valve open,

Fig. 6 is an enlarged section through the main valve element, the secondary valve element, showing their relation to each other and to the valve operating stem and the pin 10 of the valve plug.

In Fig. 1 a boiler is designated generally by the numeral 11. There is a float chamber 12 formed with a base 13 and a dome 14, the dome being connected to a steam pipe 15 attached by a fitting 16 to the top of the boiler preferably adjacent the steam dome. The base is connected by a nipple 17 to a journal fitting designated generally by the numeral 18. To the lower end of the fitting there is a pipe 19 connected to the boiler adjacent the bottom to carry water. In the float chamber there is a float 20 having a rod 21 extending downwardly therefrom. This rod is adjustably connected to one arm 22 of a fulcrum lever 23. This attachment may be in any suitable manner.

The fitting 18 is formed with a cross fitting 24 to which the pipe 19 is connected and has a pipe 25 connected thereto and threaded into the cylindrical end 26 of an attachment 27. This attachment has a partition 28 therethrough with a threaded opening 29 and has a journal plug 30 threaded therein. This plug has a bore 31 flared at 32 and is closed by a plug 33. Transversely of this plug there is a cylindrical bore 34 having an enlarged threaded section 35 for a packing gland 36 which compresses the packing 37 against the fulcrum shaft 38 of the fulcrum lever 23. It will, therefore, be seen that the arm 22 of this lever connects to the side of the fulcrum shaft 38 outside of the packing gland 36. The other arm 39 of this lever is connected to the opposite end of the shaft 38 and operates in 45 the flared section 32 of the plug.

The valve end 40 of the attachment 27 has a pipe 41 connected thereto leading to the boiler to carry the feed water. At the top there is a tubular section 42 having a valve seat 43 and surrounding this seat there is a tubular structure 44 having a closed top 45 and with slots or ports 46 therethrough. This may have a pressed fit on the structure 42. The T-fitting 47 is threaded on the tubular structure 42 forming a space 48 between the T and the tubular structure 44. The upper end of the T is closed by a plug 49 and from the stem there is a pipe 50 leading to a feed water pressure pump, this not being illustrated.

The valve construction comprises a main valve element 51 having a surface 52 to engage the seat 43 and with a cylindrical surface 53 having a sliding fit in the tube 44, but not being sufficiently tight to prevent

leakage of water past the cylindrical surface. This element 51 has a central bore 54, with a valve seat 55 at the top. A secondary valve element 56 has its lower end seated on the seat 55 and this has a sliding fit in the inner chamber 57 in the top 45. This secondary element also has a bore 58 therethrough and has a valve plug 59 forming a closure on the top, this closure having a depending pin 60. This pin is adapted to be engaged by the stem 61 of the valve rod 62 which is connected to the arm 39 of the fulcrum lever 23 by a pivotal connection 63. The rod has a collar 64 thereon.

The manner of operation and functioning of my construction is as follows: It is to be understood that the main valve element while 70 slidable in the tube 44 may allow leakage of water between the cylindrical surface 53 and the tube 44, and also that the secondary element 56 sliding in the inner chamber 57 allows leakage of water. And there is sufficient space for flow of water between the pin 60 and the bore of the secondary valve, and also a clearance for water between the stem 61 of the valve rod and the main valve element.

The operation and construction of my regulator is substantially as follows, dealing with the action under the influence of hydraulic fluid under pressure: The pressure in the feed pipe is as a rule greater than that in the boiler by an appreciable amount, and on account of there being freedom for the passage of water from the supply outside of the main valve element and to the inner chamber 57 there is a greater pressure on top of the valve plug 59 than in the pipe 41. When the level of the water in the boiler drops the valve operating rod 62 is raised and the stem 61 engages the pin 60 unseating the plug 59. This may be unseated before the stem 61 contacts with the lower edge of the secondary valve element 56. The raising of the plug 59 allows an equalization of the pressure between the inner chamber 57 and the pipe 41.

This results in there being a greater pressure in the tubular structure 44 above the main valve element than in the inner chamber 57 and this greater pressure acting on the lower end of the secondary valve element causes a lifting of such element. This action may take place even if the cross sectional area of the secondary valve element subjected to the pressure of the supply fluid is less than the area of the top of the secondary valve element 56.

Thus when the secondary element is raised by the hydraulic pressure it allows an equalization of pressure between the tubular structure 44 above the main valve element and the pipe 41. As the lower surface of the major portion of the main valve element is subjected to the pressure of the supply fluid, and this

pressure being greater than that on top of the main valve element 51, this causes a lifting of such element, and this takes place even though the area on the bottom exposed to the increased pressure is slightly less than the top surface exposed to a lesser pressure. The hydraulic pressure, therefore, lifts the main valve element 51 without the collar 64 contacting therewith and allows a free flow of water through the ports 46 into the pipe 41 leading to the boiler.

In all this action, due to the hydraulic pressure of water, the stem 61 of the valve rod 62 need not contact with the lower end of the secondary valve element 56, nor need the collar 64 contact with the lower end of the main valve element 51. It will, therefore, be seen that my construction is sensitive to changes of water level and the weight to be lifted by the valve rod 62 is very small. As shown in Fig. 5, when the main and secondary valve elements are elevated to their full extent by the hydraulic pressure the valve plug 59 contacts with the upper end 25 of the inner chamber 57 and thus limits the upward movement of the rod 62.

If for any reason the valves should stick, the operation will be as follows: The rod 62 through the medium of the stem 61 raises the pin 60 and unseats the plug 59 on the lowering of the water level in the boiler thereby allowing equalization of pressure between the chamber 57 and the pipe 41; then should the secondary valve element 56 stick the stem 61 engaging the lower end of this element thrusts it upwardly allowing equalization of pressure between the tubular member 44 above the main valve element and the pipe 41. Then should the main valve element 51 stick, the collar 64 engaging the lower end of this element raises it off its seat and allows free flow of water through the ports 46 into the pipe 41, hence to the boiler.

Various changes may be made in the principles of my invention without departing from the spirit thereof, as set forth in the description, drawings and claims.

I claim:

1. In a boiler feed regulator a main tubular valve element forming a closure between a source of liquid under pressure and the boiler, a secondary tubular valve element seated thereon, a valve plug having a depending pin seated on the secondary element, a slideable stem extending upwardly in the main element and having a collar thereon, said stem being operated by means controlled by the water level in the boiler, the stem on its first upward movement engaging the pin and lifting the plug then lifting the secondary element, and finally the collar lifting the main valve element.

2. In a boiler feed regulator as claimed in claim 1, the water level control comprising a

float in a float chamber connected to the water and steam in the boiler, the fulcrum lever connected to the float, the fulcrum of said lever having a water tight journal, and means to connect one end of the lever to the said stem, said means being cut off from liquid or steam connection with the float chamber.

3. A boiler feed regulator comprising in combination a structure forming a float chamber having its lower part connected to the water of the boiler and the upper part connected to the steam of the boiler, a float mounted therein and having a depending rod, a fitting connected to the said structure and having a partition with a closure plug therein, said plug having a central bore with a transverse bore intersecting, the transverse bore having a packing gland with packing and forming a journal for a fulcrum shaft, a fulcrum lever having one end connected to the said shaft outside of the plug and to the said rod, the other end of the fulcrum lever being connected to the shaft in the bore of the plug, a tubular valve structure having a closure element seated thereon forming a closure between a source of liquid under pressure and the boiler, a rod having a stem operatively connected to the end of the fulcrum lever fitted in the bore of the plug, said stem being adapted to elevate the valve element to allow flow of liquid.

4. A boiler feed regulator as claimed in claim 3, in addition a tubular structure in the valve forming a guide for the main valve element and having ports therethrough, an inner tube in the top of said structure, and a secondary valve element slideable therein, the stem extending through the main element and being adapted to engage the said secondary element prior to engagement with the first element.

5. A boiler feed regulator as claimed in claim 3, in addition a tubular structure in the valve forming a guide for the main valve element and having ports therethrough, an inner tube in the top of said structure, and a secondary valve element slideable therein, the stem extending through the main element and being adapted to engage the said secondary element prior to engagement with the first element, the valve plug having a depending pin forming a closure for the secondary valve element, the said pin being adapted to be engaged by the said stem in the first upward movement thereof.

6. A boiler feed regulator having a tubular main valve element with a chamber thereabove connected to a source of hydraulic pressure, the valve opening to a connection with the boiler, a tubular second valve element having a closure seated on the first element and having a chamber thereabove connected to the source of hydraulic pressure,

means operated by the water level of the boiler to open the said closure and afford a connection through the second valve element, said second element having means under the influence of the hydraulic pressure to become unseated and to allow equalization of pressure in the chamber above the first valve element and a connection to the boiler.

7. A boiler feed regulator as claimed in claim 6, the main valve element on its lower surface having a face exposed to the hydraulic pressure of the source and lifting from its seat when the pressure in the chamber above said main element is reduced.

10 8. In a boiler feed regulator a fitting having a valve seat with a tubular structure extending upwardly outside of the seat and having a closure with ports through said structure, a connection from the upper side

20 of the seat to a source of liquid under pressure and from the fitting to a boiler, a tubular main valve element bearing on the seat and slideable in the tubular structure, a secondary valve element seated thereon, a stem

25 operatively connected to a float operated by the water level of the boiler, said stem extending upwardly through the main element and being adapted to first lift the secondary element and then the main element, an inner

30 chamber in the top of the tubular structure and forming a guide for the secondary valve element, a closure plug for said secondary element having a depending pin adapted to be first engaged by the said stem, and a

35 means on the stem to engage the main valve element.

9. A boiler feed regulator comprising in combination a structure forming a float chamber with a connection to the water and to the steam of the boiler, a float therein, a fitting having a water tight journal with a fulcrum shaft mounted therein, a fulcrum lever connected to said shaft and to the float,

40 a tubular valve structure having a reciprocating valve rod with a stem operatively connected to the fulcrum lever to be reciprocated by said lever, and a valve forming a closure between a source of liquid under pressure and the boiler, said valve being operated by the said stem, the said fitting having

45 a journal plug with a transverse bore, and a packing gland with packing forming the journal for the fulcrum shaft, one end of the fulcrum lever being connected to said shaft

50 outside of the plug and the other end to the shaft inside of the plug.

55 In testimony whereof I have signed my name to this specification.

THEOPHILUS KALLMEYER.
